UNITED STATES PATENT OFFICE

2,327,161

MARINE BOILER

John Phillips Badenhausen, Philadelphia, Pa.

Application April 24, 1941, Serial No. 390,167

5 Claims. (Cl. 122—473)

This invention relates to marine boilers. In the marine boilers heretofore available and at present in use, the design of the boiler is such that the boilers have an unnecessarily limited steam production, are wasteful of space on the ship by reason of their design and require large aisles, alleyways, and clearances with respect to adjoining boilers for operating. The effective use of the space on the ship, particularly on ships now being built and under design, is a consideration of major importance and the marine boilers heretofore available did not meet the requirements.

In the marine boilers heretofore employed, the location of the burners or firing doors was such that upon the entry of water into the boiler room, by reason of an outside explosion or the like, a slight rise in the water level would result in extinguishing the fire in the boiler. The failure of the boilers would render the ship unable to continue in operation. At this critical juncture the pumps would likewise discontinue operation because of lack of steam.

It is accordingly an object of the present invention to provide an improved marine boiler which will have a higher steam output for the space used and which will permit of a reduction of the space allotted to aisles and alleyways.

It is a further object of the present invention to provide a marine boiler having a higher rate of heat release than has heretofore been obtainable.

It is a further object of the present invention to provide a marine boiler which will have a greater measure of safety under adverse conditions than heretofore.

Other objects of the invention will appear from the annexed specification and claims.

The nature and characteristic features of the invention will be more readily understood from the following description, taken in connection with the accompanying drawings forming part hereof, in which:

Figure 1 is a vertical central sectional view of a marine boiler in accordance with the present invention;

Fig. 2 is a top or plan view of the boiler shown in Fig. 1;

Fig. 3 is a horizontal sectional view taken approximately on the line 3—3 of Fig. 1;

Fig. 4 is an enlarged fragmentary view taken approximately on the line 4—4 of Fig. 1 and showing the arrangement of the wall tubes;

Fig. 5 is a fragmentary sectional view taken approximately on the line 5—5 of Fig. 1 showing

the arrangement of certain of the tubes to provide a screen;

Fig. 6 is a fragmentary sectional view taken approximately on the line 6—6 of Fig. 1 and showing the arrangement of certain of the tubes to provide a screen; and

Fig. 7 is a fragmentary sectional view taken approximately on the line 7—7 of Fig. 1 and showing the arrangement of certain of the tubes to provide a screen.

It will, of course, be understood that the description and drawings herein are illustrative merely, and that various modifications and changes may be made in the structure disclosed without departing from the spirit of the invention.

Referring more particularly to the drawings in which a preferred embodiment of a marine boiler in accordance with the present invention is illustrated, an external casing 10 is provided preferably consisting of a bottom portion or floor 11, a vertical wall 12, a vertical wall 13, and vertical walls 14 and 15. The vertical walls 12, 13, 14, and 15 are preferably secured to the bottom wall 11 in fluid-tight relationship to prevent access of water into the interior of the casing 10. The particular disposition of the boiler and casing within the hull will be dependent upon the size and design of the ship. In some instances the walls 12 of a pair of boilers will be face to face, with a clearance therebetween of the order of two feet while in others the walls 13, 14 or 15 will be similarly located. For purposes of convenience the wall 12 will be referred to as a front wall and the other walls identified in their relation to that wall although it will be understood that other walls may, if desired, be arranged to occupy a frontal position.

The boiler proper is disposed within the casing 10 and includes adjacent but spaced from the wall 13 a horizontal steam and water drum 20. The drum 20 is preferably parallel to the wall 13. A horizontal water drum 21 is provided at the bottom of the casing 10, is disposed parallel to the drum 20, and preferably is spaced from the wall 13 a greater distance than the drum 20.

Lower water wall headers 22 are provided extending horizontally from adjacent the drum 21 toward the wall 12 and at the bottom of the casing 10 along the interior of each of the walls 14 and 15. Horizontal upper wall headers 23 are also provided above the wall headers 22 and along the interior of each of the walls 14 and 15.

The wall headers 23 are disposed adjacent the upper sides of the walls 14 and 15. Side banks

of tubes 25 are provided extending from the lower headers 22 to the upper headers 23, the tubes 25 being closely spaced and in contact to provide boundary walls for the main combustion space A. Refractory material 26 may, if desired, be provided between the tubes 25 and the casing walls 14 and 15. The lower water headers 22 are connected to the water drum 21 by banks of tubes 27 which supply water to the headers 22. The upper headers 23 are connected to the steam and water drum 20 by banks of tubes 28 for delivery of steam to the drum 20. The lower water header is connected to the upper steam and water drum 20 by means of a plurality of banks of tubes preferably as hereinafter pointed out.

The uppermost portion of the water drum 21 is preferably connected to the steam and water drum 20 by a central bank of tubes 29 from side wall 14 to side wall 15, and substantially vertically for the greater portion of their extent. The tubes 29 up to the point 30 are closely spaced and in contact to provide a wall or baffle. The tubes 29 above the upper part of the wall or baffle are alternately disposed out of the plane of the wall or baffle as illustrated at 31, and in a manner similar to the tubes shown in Fig. 7.

A marginal bank of tubes 35 is provided from side wall 14 to side wall 15 and preferably extending from the mid-portion of the side of the water drum 21. The tubes 35 of this bank extend first substantially horizontally and then upwardly and then to the steam and water drum 20, alternate tubes 35 being offset as indicated at 36 (see Figs. 3 and 7). The tubes extend from the point 37 upwardly in alignment, the tubes 35 being closely spaced and in contact to provide a wall or baffle. The space between the central bank of tubes 29 and the marginal bank of tubes 35 and between the side wall 14 and the side wall 15 is preferably substantially filled with steam generating tubes 38 extending from the water drum 21 to the upper steam and water drum 20.

Another marginal bank of tubes 40 is provided, the tubes 40 from the side wall 14 to the side wall 15 extending substantially horizontally from the water drum 21 at the mid-portion of the side thereof and then vertically upward. The lower portions of the tubes 40 are alternately disposed in different vertical planes as at 41 (see Fig. 6) and the tubes 40 from the point 42 upwardly to the steam and water drum 20 are disposed in alignment. The tubes 40 from the point 42 upwardly are preferably closely spaced and in contact to provide a wall or baffle. The space between the central bank of tubes 29 and the marginal bank of tubes 40 and between the side wall 14 and the side wall 15 is substantially filled with tubes 45 which extend from the lower water drum 21 to the upper steam and water drum 20. The wall or baffle consisting of the tubes 40 serves as one of the boundary walls of the main combustion space A, as hereinafter more fully referred to.

An upward pass is thus provided between the marginal bank of tubes 40 and the central bank of tubes 29 so that gases may pass around the lower end of the baffle formed by the tubes 40 and upwardly and then around the upper end of the wall or baffle formed by the tubes 29 and downwardly in a downward pass between the central bank of tubes 29 and the marginal bank of tubes 35.

A lower header 50 is provided, spaced from the wall 12, and an upper header 51 is provided preferably substantially vertically above the lower

header 50 and parallel thereto and to the drum 20. The lower water drum 21 is connected to the lower header 50 by a bank of floor tubes 52 which are preferably closely spaced and in contact. The lower header 50 is preferably connected to the upper header 51 by a bank of tubes 53, the lower portions 54 of which are disposed alternately in parallel planes (see Figs. 1 and 5). The tubes 53 from the point 55 upwardly to the upper header 51 are preferably closely spaced and in contact to provide a wall or baffle which serves as another boundary wall for the main combustion space A. The upper header 51 is preferably connected to the upper steam and water drum 20 by a bank of top wall tubes 56, the tubes 56 being shaped for the purposes hereinafter referred to. The top wall of the main combustion space preferably consists of refractory material 57 disposed immediately above and resting upon the tubes of the bank of tubes 56 and is provided with a plurality of burner openings as hereinafter more fully referred to. The tubes 56 of the top wall bank are preferably shaped in such a manner as to avoid any obstruction of the burner openings. The main combustion space A is thus bounded by the top wall bank of tubes 56, side banks of tubes 25, the bank of tubes 40, the bank of tubes 53 and the floor bank of tubes 52.

Burners 60, which may be of any desired type in accordance with the fuel to be burned, are provided in the burner openings. The fuel employed is preferably pulverized bituminous coal, although if desired oil may be employed. The burners 60 are preferably adjustable to vary the delivery of fuel and air as desired.

An additional or auxiliary combustion chamber B is provided between the side banks of tubes 25, the bank of tubes 53 and the casing wall 12. A bank of closely spaced tubes 62 is provided which extends from the lower header 50, and has an upwardly inclined lower portion 63. The tubes of this bank 62 extend substantially vertical and parallel to the wall 12 as at 64, and then, at approximately the level of the upper header 51, extend substantially horizontal as at 65 and into the upper header 51. The tubes of the bank of tubes 62 are preferably closely spaced to provide a lower and side wall or baffle.

The horizontally extending portions 65 of the tubes of the bank of tubes 62 preferably have refractory material 66 disposed thereabove to provide the top wall of the additional combustion chamber B.

The additional or auxiliary combustion chamber is thus bounded by the bank of tubes 62 which provide an inclined bottom wall 63, a front wall 64, and a top wall 65 and by the side banks of tubes 25. The top wall portion 66 is provided with a plurality of burner openings in which suitable adjustable burners 68 are mounted, the burners 68 being of any desired type in accordance with the fuel to be burned.

An outer top wall portion 70 is provided, is disposed parallel to the top wall portions 57 and 66, respectively, and is spaced therefrom to provide a passageway for the supplying of air to the burners 60 and to the burners 68. If desired, an air heating space 71 may be provided in the space between the bank of tubes 62 and the wall 12 of the casing 10.

The auxiliary combustion space B is preferably utilized for the primary purpose of superheating the steam delivered from the steam and water drum 20. A superheater header 75 is provided preferably vertically above the upper header 51.

The steam and water drum 20 is connected to the superheater header 75 by means of suitable steam lines 76. At the top of the casing wall 12 and parallel to the superheater header 75 a superheater steam outlet header 77 is provided.

The superheater tubes connecting the superheater header 70 to the superheater outlet header 77 preferably comprise a plurality of spaced superheater tubes which extend downwardly from the superheater header and vertically in substantially parallel spaced relationship to the wall or baffle as at 78 and then at the lower part thereof are inclined as at 79 toward and connected into a superheater drain header 80. The superheater drain header 80 is disposed at the lower portion of the casing 10 along the interior of the casing wall 12. A plurality of superheater tubes 81 also extend from the superheater header 80 upwardly, inside the wall or baffle at 84 in spaced relationship thereto, to the superheater outlet header 77.

In the space between the marginal bank of tubes 35 and the casing wall 13 an economizer 85 may be provided, the economizer 85 being connected at the outlet portion thereof to the steam and water drum 20. An additional economizer section 86 may also be provided, if desired, above the economizer 85 and between the steam and water drum 20 and the casing wall 13 for supplying partially heated water to the economizer section 85.

The mode of operation of the marine boiler of the present invention will now be briefly pointed out. Two distinct sets of conditions must be met in normal operation. For forward operation of the ship, a large and variable quantity of steam at predetermined pressure and superheated to the desired extent is required. For reverse operation of the ship, a lesser quantity of steam is required and this is desired without superheating. These conditions are adequately met in the manner hereinafter referred to.

For forward operating conditions, the fuel is supplied to the burners 60 for the main combustion chamber A and to the burners 62 for the auxiliary combustion chamber B. The fuel supplied to the burners 60 is burned in the combustion space A between the side banks of tubes 25, the bank of tubes 53, the marginal bank of tubes 40 and the floor bank of tubes 52. The heat released by the combustion is effective for generating steam in the tubes surrounding the combustion space A. The burning gases pass downwardly in the main combustion space A and from that space through the screen at 41 provided between the offset tubes of the marginal bank of tubes 40 and then into the upward pass. In the upward pass, the hot gases of combustion in contact with the tubes of the bank of tubes 45 are also effective for generating steam. The gases then pass around the top of the wall or baffle of the central bank of tubes 29, and downwardly in the downward pass where additional heat is given up for the generation of steam in the tubes of the bank of tubes 33. The gases then pass through the screen provided between the tubes at 36. The gases then pass upwardly, through the economizer section 85 and through the upper economizer section 86 where further heat is given up, and then to the stack.

The fuel introduced through the burners 60 into the additional combustion space B burns therein and the major portion of the heat which is released is utilized for superheating the steam in the superheater tubes 78 and 81. At the same

time, the tubes at 62, the wall tubes at 53, and the side wall tubes 25 absorb some of the heat so that a relatively smaller quantity of steam will be generated in the walls of the additional combustion space B. By reason of the nature of the walls of the auxiliary combustion space B, there is no danger of destruction thereof by the heat released within that space. The gases from the auxiliary combustion space B pass downwardly within that space and through the screen provided by the offset tube portions 54 and into the lower part of the main combustion space A where they mingle with the gases of combustion in that space and pass therefrom with the other gases for steam generation as hereinbefore indicated.

It will be noted that the principal steam generation is effected with the fuel supplied through the burners 60 to the main combustion space A, the quantity of fuel being regulated in accordance with the steam requirements. The heat for superheating the steam is released within the auxiliary combustion space B with some additional steam generation in the water cooled walls surrounding that space.

In many marine installations, it is not customary to employ superheated steam for operating the reversing engines. The marine boiler of the present invention is particularly adapted for the rapid change in operating conditions required for reversing since the burners may be readily adjusted as desired. For reversing conditions the burners 62 are shut off. The steam will be delivered as before from the steam and water drum 20 through the superheater tubes 78 and 81 without the addition of any substantial quantity of heat thereto in the auxiliary combustion space B, since the burners 62 have been shut off. At the same time, the superheater tubes 78 and 81 are protected from overheating by the steam passing therethrough.

When forward operation is again desired, the burners 62 may be started up and within a very short interval of time, the desired output of superheated steam will be available.

As illustrative of the compact and highly effective character of the marine boiler of the present invention, it may be pointed out that the same may be enclosed with a space of approximately twenty feet between the casing walls 12 and 13, ten feet between the casing walls 14 and 15, with a height from the bottom of the lower water drum 21 to the top of the steam and water drum 20 of approximately sixteen feet. A capacity of the order of 480,000 pounds of steam per hour at a pressure of 600 pounds and a temperature of 850° Fahrenheit will be available. The heat release may range as high as 500,000 B. t. u. per hour per cubic foot of furnace volume, and 1,200,000 B. t. u. per hour per square foot of radiant heat absorbing surface, if desired. At the same time, the steam temperature and quantity may be readily varied as required for reversing operations.

I claim:

1. In a marine boiler, two combustion chambers, a steam and water drum, a lower header, an upper header above said lower header and connected to said drum, closely spaced contacting vertical water tubes connecting said headers and forming a common wall between said two combustion chambers, said tubes having portions offset from said wall for the discharge of gases of combustion from one chamber into the other chamber, a bank of tubes connecting said lower header and said upper header, the tubes of said

bank extending forwardly from said lower header to provide a lower wall and upwardly to provide a vertical wall for one of said combustion chambers, additional steam generating tubes lining other walls of said combustion chambers and connected to said drum, superheater tubes in one of said chambers exposed to the radiant heat of the burning fuel in said chamber, and separate fuel and air supplying means in the upper portions of each of said chambers.

2. In a marine boiler, a casing, two combustion chambers within said casing each having a horizontal top wall, a lower header, an upper header above said lower header and connected to said drum, closely spaced contacting vertical water tubes connecting said headers and forming a common wall for said two combustion chambers, said common wall having portions open for the discharge of gases of combustion from one chamber into the other chamber, a bank of tubes connecting said lower header and said upper header, the tubes of said bank extending forwardly from said lower header to provide a lower wall then upwardly to provide a vertical front wall and then rearwardly to provide a top wall for one of said combustion chambers, superheater tubes in one of said chambers exposed to the radiant heat of the burning fuel in said chamber, and separate fuel and air supplying means in the top wall of each of said chambers.

3. A marine boiler including a casing having a bottom wall with vertical side walls and open at the top, an upper steam and water drum adjacent one of the side walls, a lower water drum below said upper drum and parallel thereto, steam generating tubes extending between said drums and divided into a plurality of passes, an upper header parallel to and spaced from said steam and water drum and connected thereto by a plurality of tubes extending along the top of a first combustion chamber, a lower header parallel to and below said upper header, closely spaced contacting vertical tubes connecting said headers and providing a front boundary wall for the first combustion chamber, closely spaced tubes extending from the lower header to the lower drum and providing a lower boundary wall for the combustion chamber, upper and lower side wall headers arranged along each of a pair of opposed vertical side walls, closely spaced tubes respectively connecting the lower and upper headers of each side and providing boundary walls for the respective sides of the said combustion chamber, the top of the combustion chamber being provided with fuel inlet means for supplying fuel and air downwardly into said combustion space, a second combustion chamber within said casing, a bank of tubes extending from said lower header to said upper header and providing a front wall for said second combustion chamber, one of the walls of said second combustion chamber consisting of the front wall of said first combustion chamber, fuel inlet means in the top wall of said second combustion chamber for supplying fuel and air downwardly into the second combustion chamber, and superheater tubes in said second combustion chamber exposed to the radiant heat of the burning fuel in said chamber.

4. A marine boiler including an upper steam

and water drum, a lower water drum below said upper drum and parallel thereto, banks of steam generating tubes extending between said drums, an upper header parallel to and spaced from said steam and water drum, a lower header parallel to and below said upper header, closely spaced contacting vertical tubes connecting said headers and providing a front boundary wall for a first combustion chamber, closely spaced tubes extending from the lower header to the lower drum and providing a lower boundary wall for said combustion chamber, upper and lower side wall headers arranged along each of a pair of opposed side wall portions, closely spaced tubes respectively connecting the lower and upper side wall headers and providing boundary walls for the respective sides of said combustion chamber, a top wall portion provided with fuel inlet means for supplying fuel and air downwardly into said combustion chamber, a second combustion chamber within said casing, a bank of tubes extending from said lower header to said upper header and providing a plurality of walls for said second combustion chamber, the front wall of said first combustion chamber constituting the rear wall of said second combustion chamber and having portions shaped to provide communication between said chambers, fuel inlet means for supplying fuel and air downwardly into the second combustion chamber, and superheater tubes in said second combustion chamber exposed to the radiant heat of the burning fuel in said chamber.

5. A marine boiler including a casing having a horizontal bottom wall and vertical side walls secured thereto, an upper steam and water drum adjacent the rear side wall, a lower water drum below said drum and parallel thereto, steam generating tubes extending between said drums, an upper header parallel to and spaced from said steam and water drum, a lower header parallel to and below said upper header, closely spaced contacting vertical tubes connecting said headers and providing a front boundary wall for a first combustion chamber, closely spaced horizontal tubes extending from the lower header to the lower drum and providing a lower boundary wall for said combustion chamber, upper and lower side wall headers arranged along each of a pair of opposed vertical side walls, banks of closely spaced vertical tubes respectively connecting the lower and upper side wall headers and providing boundary walls for the respective sides of said combustion chamber, a top wall portion provided with fuel inlet means for supplying fuel and air downwardly into said combustion chamber, a second combustion chamber within said casing, the tubes of the front boundary wall of the first combustion chamber providing a rear boundary wall of said second combustion chamber, a bank of tubes extending from said lower header to said upper header and providing a bottom, front and top wall for said second combustion chamber, fuel inlet means in the top wall of said second combustion chamber for supplying fuel and air downwardly into the second chamber, and superheater tubes in said second combustion chamber exposed to the radiant heat of the burning fuel in said chamber.

JOHN PHILLIPS BADENHAUSEN.
